UNITED STATES PATENT OFFICE.

GREGORY C. DAVISON, OF NEW LONDON, CONNECTICUT, ASSIGNOR TO ELECTRIC BOAT COMPANY, OF NEW YORK, N. Y., A CORPORATION OF NEW JERSEY.

REVERSIBLE INTERNAL-COMBUSTION ENGINE.

1,230,132.

Specification of Letters Patent. Patented June 19, 1917.

Application filed May 5, 1915. Serial No. 25,903.

To all whom it may concern:

Be it known that I, GREGORY C. DAVISON, a citizen of the United States, residing at New London, in the county of New London and State of Connecticut, have invented certain new and useful Improvements in Reversible Internal-Combustion Engines; and I do hereby declare the following to be a full, clear, and exact description of the invention, such as will enable others skilled in the art to which it appertains to make and use the same.

This invention relates to internal combustion engines and more particularly, to the construction of such engines whereby they may be reversed and operated in either direction. The invention may be employed in internal combustion engines of various types but is of special utility in internal combustion engines employing liquid oil as the fuel and operating on the Diesel cycle.

In order to provide for the reversing of an internal combustion engine, it has been common heretofore to provide two cams for operating each of the several valves; with this construction the operation of reversing involves raising the valve-lifters free of the cam-shaft, then sliding the cam-shaft axially so that one set of cams is rendered inoperative and the other operative and then lowering the valve-lifters into coaction with the cam-shaft. This construction involves the use of numerous parts whose operation is not as smooth and reliable as is desired. The present invention is directed to the provision of an improved construction whereby an internal combustion engine is adapted for reversal, this construction involving the use of a less number of parts which will operate in a smooth and reliable manner.

It has been proposed heretofore to provide means for turning the cam-shaft of an internal combustion engine angularly in its bearings relatively to the crank-shaft of the engine so as to carry the cams on the cam-shaft from the positions for operating the engine in one direction to the positions for operating the engine in the opposite direction. This expedient, however, is unsatisfactory for the reason that all of the valves are shifted angularly the same amount. I have found that provision may be made for the reversal of an internal combustion engine in a simple and effective manner by employing separate cam-shafts for

the several cams of each cylinder of an engine and mechanism for shifting these cam-shafts individually so that each may be shifted the amount which is found to be desirable in order to secure proper operation of the engine in the reverse direction. The several mechanisms for shifting the cam-shafts may be operated simultaneously by a single operating device, but by reason of the employment of a plurality of cam-shafts, one for each cam or set of cams, which shafts may be shifted predetermined but different amounts, the cams may be established in the relation to the engine shaft which is found to be most conducive to proper operation in the reverse direction. In a multi-cylinder engine, the several cam-shafts may extend along the whole series of cylinders and each shaft may carry all of the cams of one set, that is, all of the cams for operating the inlet valves of all of the cylinders or all of the cams for operating the exhaust valves of all of the cylinders; in no case, however, are cams of two different sets, as for instance, a cam for operating an exhaust valve and a cam for operating an inlet valve, mounted upon the same cam-shaft.

I have illustrated one form in which the invention may be embodied in the accompanying drawings which show an engine of the Diesel type, but it will be understood that the invention may be employed in other forms of internal combustion engines whether operating on the Diesel cycle or not and in engines having valve gears differing materially in construction from that illustrated.

In the drawings, Figure 1 is an end view of an internal combustion engine; Fig. 2 is an elevation of a portion of the engine, Figs. 3 and 4 are detailed views of the operating device for shifting the cam-shafts angularly and Figs. 5, 6, 7 and 8 are diagrammatic views illustrating the action of the cams and the parts operated thereby.

Referring to these drawings, an internal combustion engine is shown having a casing 9 upon which are mounted a plurality of cylinders 10; a piston reciprocates in each of these cylinders and the several pistons are connected to cranks on the crank-shaft 11 which is mounted for rotation in bearings formed on the casing 9. Each cylinder 10 has an exhaust valve 12 and in the present instance this exhaust valve is shown as oper-

100

95

110

ated by a pivoted lever 13 one end of which carries a member which is adapted to engage and operate the exhaust valve 12; the other end of this lever 13 carries a roller which 5 bears on the periphery of a cam 14 carried by a cam-shaft 15 mounted for rotation in suitable bearings secured to the casing 9. Each cylinder is also provided with an inlet valve 16 which is here shown as operated by 10 a pivoted lever 17, one end of which carries a member which is adapted to engage and operate the inlet valve 16; the other end of this lever 17 carries a roller which runs upon the periphery of a cam 18 secured to a 15 cam-shaft 19 which is mounted for rotation in bearings on the casing 9. The engine illustrated being of the Diesel type, a spray valve is shown at 20; this valve is operated by a bell-crank lever 21 pivoted in a bracket 20 secured to the cylinder 10 and the bell-crank 21 is operated by a pivoted lever 22, one end of which carries a member which is adapted to engage and operate the bell crank 21; this lever 22 carries at its other end a roller 25 which travels on the periphery of a cam 23 secured to a cam-shaft 24 mounted for rotation in bearings directly above the cam-shaft 19.

As many cylinders 10 may be provided as 30 is desired, the additional cylinders being arranged at the left of the one shown in Fig. 2 with all of the cylinders in line and with the cam-shafts 15, 19 and 24 extending along all of the cylinders. Each of the cam-shafts 15, 35 19 and 24 carries all of the cams of one set, that is, the shaft 15 carries the cams for operating the exhaust valves of all of the cylinders, the shaft 19 carries the cams for operating the inlet valves of all of the cylinders, 40 and the shaft 24 carries the cams for operating the spray valves of all of the cylinders. In no case are cams of two different sets, as for instance, a cam for operating an exhaust valve and a cam for operating an inlet valve, 45 mounted upon the same cam-shaft.

In order to effect the reversal of the direction of operation of the engine, the cam-shafts 15, 19 and 24 are turned angularly in their bearings relatively to the crank-shaft 50 11 so as to carry the cams on the cam-shafts to new positions in which they will operate in the manner appropriate to the running of the engine in the reverse direction. But the mechanism for effecting this angular shift 55 of the cam-shafts includes individual connections to each of the several cam-shafts so that those shafts may be turned different angular amounts. Preferably, a single operating device is employed for effecting the 60 angular shift of all of the cam-shafts, but the construction is such that the direction and magnitude of the movement of one cam-shaft is in no way dependent upon the direction and magnitude of the movement of another cam-shaft.

The several cam-shafts are driven from the crank-shaft in any suitable manner. In the present instance, I have shown for this purpose vertical shafts 25 and 26 having spiral gears 27 on their lower ends which 70 mesh with the spiral gear 28 on the crank-shaft 11. At their upper ends the shafts 25 and 26 carry bevel gears 38 which mesh with similar gears upon the shafts 15 and 19. The shaft 24 is driven from the shaft 19 by 75 coacting gears 29 (Fig. 4). The sizes of these several gears are such that the shafts 15 and 19 are driven at one-half of the speed of the crank-shaft 11 and the shaft 24 rotates in unison with the shaft 19. Between 80 the cams on the shafts 24, 19 and 15, and the gears by which those shafts are driven, each of the shafts is divided as shown in Fig. 4 and on each shaft is an axially movable sleeve for effecting the connection between 85 the two parts of the shaft. Each sleeve 30 has at one end thereof a spline connection 31 to one part 32 of the divided shaft. At the other end of the sleeve a plurality of blocks or shoes 33 are secured to the sleeve 90 within the opening therein and in positions to enter spirally arranged grooves provided for their reception in the end of the cam-shaft proper, as shown at 34 in Fig. 4. A sleeve connection of this construction is employed in connection with each of the three cam-shafts 15, 19 and 24, but the pitch of the spiral grooves 34 in the three cam-shafts is not the same. The three sleeves 30 may be moved axially simultaneously by a single 95 operating device and when they are so moved, they turn the cam-shafts relatively to the crank-shaft by amounts determined by the pitch of the several threads 34. Each of the sleeves 30 has a circumferential groove 10 formed therein to accommodate a ring as shown in Fig. 4 which ring receives the ends of screws 35 carried by a yoke 36. This yoke may be moved back and forth in any suitable manner, that is, manually, pneumatically or 11 in any other desired manner. In the present instance, a pivoted operating lever is shown at 37 pivoted upon the casing of the engine and connected to the yoke 36 so as to operate the same. It will be seen that by moving the operating device 37 from one limit of its 1 range of movement to the other, the three cam-shafts and all of the cams thereon will be shifted angularly independently of the crank-shaft and that the extent and direction of movement of the cams of one set will not be affected by or dependent on the extent or direction of movement of the cams of another set, but on the contrary will depend wholly upon the pitch of the grooves 134 provided in the cam-shaft. In the case of a Diesel engine of the construction shown in Figs. 1 and 2, the spirally arranged grooves in the ends of the cam-shafts may be 1 such that movement of the operating device 1

37 from one limit of its range of movement to the other will cause the exhaust cam-shaft 15 to be turned backward approximately 90°, the inlet cam-shaft 19 to be turned forward approximately 90°, and the cam-shaft 24 for the spray valves to be turned ahead somewhat less than 90°. This extent and direction of movement of the cam-shafts will carry all of the cams from the positions appropriate for running ahead to positions appropriate for running astern.

The diagrams in Figs. 5 to 8 illustrate the movements of the cams throughout one cycle of operations when running ahead and when running astern. The raised portions of the several cams are shown in full lines in the four figures in the positions which they occupy when running ahead and in dotted lines in the positions they occupy when running astern. The direction of rotation of the crank-shaft when the engine is running ahead is indicated by the arrow on Fig. 5 and the direction of rotation of the crank-shaft when the engine is running astern is indicated by the arrow on Fig. 8. Also, the arrows applied to the cams on Fig. 5 indicate the direction of rotation of the cam-shafts when running ahead and the arrows applied to the cams on Fig. 8 indicate the direction of rotation of the cam-shafts when running astern. Following the operation of the engine when running ahead, Fig. 5 shows the piston at the beginning of the downward stroke when air 35 is admitted to the cylinder in order to fill the cylinder with pure air. It will be seen that the raised portion of the inlet cam 18 is about to open the inlet valve 16 and that the exhaust valve 12 and spray valve 20 are closed. The piston moves downward to the position shown in Fig. 6 and during this half rotation of the engine shaft, the cam-shaft is turned through one-quarter of a revolution at the end of which the raised portion of the inlet cam 18 passes beyond the coating lever 17 so that the inlet valve 16 closes. The piston then moves upwardly in the cylinder compressing the air therein, all of the valves remaining closed. At 40 the end of the upward movement of the piston the raised portion of the spray cam 23 operates to open the spray valve 20, as shown in Fig. 7, so that the charge of fuel is admitted to the cylinder. The spray valve closes immediately and the charge of fuel, becoming ignited, expands and drives the piston downwardly to the position shown in Fig. 8. Then as the piston starts upwardly again the exhaust cam 14 opens the 45 exhaust valve 12, as shown in Fig. 8, so that during the upstroke of the piston, the products of combustion are expelled through the exhaust valve.

In order to reverse the direction of operation of the engine, the operating lever 37 is

moved as above described and the cams are shifted from the full line positions to the dotted line positions; the exhaust cam 14 is turned backward approximately 90°, the inlet cam 18 is turned ahead approximately 70 90°, and the spray cam 23 is turned ahead somewhat less than 90°, the words "backward" and "ahead" being here used with reference to the arrows on Fig. 5 indicating the direction of rotation of the cam-shafts 75 when the engine is running ahead. Following the operation when running astern, Fig. 8 shows the parts in the positions they occupy at the beginning of the compression stroke. The raised portion of the inlet cam 80 has just passed by the roller on the end of the lever 17 so that the inlet valve 16 has closed after admitting pure air to the cylinder. The piston moves up, compressing the air in the cylinder and at the end of the upstroke, the parts being then in the position shown in Fig. 7, the spray valve is opened momentarily so as to admit fuel to the cylinder. This fuel is ignited and by its expansion moves the piston down to the position 85 shown in Fig. 6. As the piston starts on its upward movement, the exhaust cam opens the exhaust valve so that the products of combustion may flow out of the cylinder during the upward movement of the piston 90 which carries the parts to the positions shown in Fig. 5. When these positions are reached, the inlet valve 16 is opened by its cam 18 so that pure air is admitted to the cylinder 95 while the piston is moving down to the Fig. 100 8 position.

In engines of the character illustrated, it is usual to provide means whereby the engine may be started by compressed air. Provision may be made for starting in this 105 manner in combination with the construction illustrated in the drawings, but as any suitable form of compressed air starting mechanism may be employed, illustration and description thereof in connection with 110 the present invention is believed to be unnecessary.

What I claim is:

1. A reversible internal combustion engine of the Diesel type comprising the combination of a cylinder, a piston reciprocating therein, a crank-shaft to which the piston is connected, inlet, exhaust and spray valves for the cylinder, three cams for operating said valves, means for causing the 115 crank-shaft to rotate said cams, and means for shifting the cams predetermined but different amounts relatively to the crank-shaft to position the cams for operation of the engine in the reverse direction; substantially 120 125 as described.

2. A reversible internal combustion engine comprising the combination of a cylinder, a piston reciprocating therein, a crank shaft to which the piston is connected, three 130

- 4
- 5 valves for the cylinder, three cams each adapted to actuate one of the valves, means for causing the crank shaft to rotate said cams, and a single means for shifting the three cams angularly predetermined amounts, one of them an amount different from the others, to position the cams for operation of the engine in the reverse direction; substantially as described.
- 10 3. A reversible internal combustion engine of the Diesel type, comprising the combination of a cylinder, a piston reciprocating therein, a crank shaft to which the piston is connected, inlet, exhaust and spray
- 15 valves for the cylinder, three cams each operating one of said valves, three shafts each carrying one of the cams, means for causing the crank shaft to rotate all of the cam-shafts, and a single means for shifting all
- 20 three of the cam-shafts angularly predetermined amounts relatively to the crank shaft to position the cams for operation of the en-

gine in the reverse direction; substantially as described.

4. A reversible internal combustion engine of the Diesel type comprising the combination of a cylinder, a piston reciprocating therein, a crank shaft to which the piston is connected, inlet, exhaust and spray valves for the cylinder, three cams for operating said valves, means for causing the crank shaft to rotate said cams, and means for shifting the three cams angularly relatively to the crank shaft predetermined amounts, one of them an amount different from the others, to position the cams for operation of the engine in the reverse direction; substantially as described.

In testimony whereof I affix my signature, in presence of two witnesses.
